United States Patent Office

Des. 192,556
Patented Apr. 10, 1962

192,556

HANDLE

Edward F. Joyce 3rd, 205 Rockaway St., Boonton, N.J.

Filed Jan. 18, 1960, Ser. No. 59,074

Term of patent 3½ years

(Cl. D10—8)

FIG. 1 is a front right end perspective view of a handle showing the new design, the front left end being substantially the same;

FIG. 2 is a bottom plan view of the handle illustrated in FIG. 1; and

FIG. 3 is a sectional view of the handle taken along the line 3-3 of FIG. 1.

I claim:

The ornamental design for a handle, as shown and described.
